UNITED STATES PATENT OFFICE.

ANDREW SNOW, JR., OF NEW BEDFORD, MASSACHUSETTS.

DESIGN FOR A TRAY.

SPECIFICATION forming part of Design No. 27,887, dated November 23, 1897.

Application filed December 30, 1896. Serial No. 617,511. Term of patent 7 years.

To all whom it may concern:

Be it known that I, ANDREW SNOW, Jr., a citizen of the United States, residing at New Bedford, in the county of Bristol and State of Massachusetts, have invented and produced a new, useful, and original Design for a Tray or other Receptacle, of which the following is a specification, reference being had to the accompanying drawings, in which—

10 Figure 1 represents a plan view of the tray, showing my new design; and Fig. 2 is a side elevation of the same.

The leading feature of my invention consists in a tray or other receptacle with upwardly-curving side edges, said tray being substantially in the outline configuration of a heart, such as is commonly seen on a play-

ing-card, and having the bead-like ornamentalations upon its upper edge.

a denotes the body of the tray, *b* the edge 20 of its upwardly-curved sides, and *c c* the bead-like ornamentalations referred to.

What I claim, and desire to secure by Letters Patent, is—

The design for a tray, substantially as shown 25 and described.

In testimony whereof I have signed my name to this specification, in the presence of two subscribing witnesses, on this 18th day of November, A. D. 1896.

ANDREW SNOW, JR.

Witnesses:

EDWARD S. BEACH,
N. L. FROTHINGHAM.
